Primary Examiner — Jeffrey D Asch*Assistant Examiner* — Rebekah A Caruso*(74) Attorney, Agent, or Firm* — Soroker Agmon Nordman(57) CLAIM

The ornamental design for a shoe, as shown and described.

DESCRIPTION

FIG. 1 is a right side view of the shoe in my new design; FIG. 2 is a left side view of the shoe thereof;

FIG. 3 is a front view of the shoe thereof;

FIG. 4 is a bottom view of the shoe thereof;

FIG. 5 is a rear view of the shoe thereof; and,

FIG. 6 is a top view of the shoe thereof.

The broken line showing of a portion of the shoe is included for the purpose of illustrating environment that forms no part of the claimed design.

1 Claim, 6 Drawing Sheets(56)
